UNITED STATES PATENT OFFICE.

MAX GILBERT, OF BRONX, AND THOMAS GUIDA AND SOLOMON KATZ, OF BROOKLYN,
NEW YORK.

BOBBIN-THREAD-SUPPLY HOLDER AND GUIDE.

Application filed May 1, 1924. Serial No. 710,238.

To all whom it may concern:

Be it known that we, MAX GILBERT, a citizen of the United States, residing at Bronx, county of Bronx, and State of New York, 5 THOMAS GUIDA, a citizen of the United States, residing at Brooklyn, county of Kings, and State of New York, and SOLOMON KATZ, a citizen of Russia, but having taken out his first papers in the United 10 States, residing at Brooklyn, county of Kings, and State of New York, have invented a certain new and useful Bobbin-Thread-Supply Holder and Guide, of which the following is a specification.

15 This invention is a thread holder so constituted as to render it highly efficient in supporting a large roll of thread in a position convenient to the bobbin of a machine and embodying means for guiding said 20 thread during the winding thereof on a bobbin.

In large manufacturing establishments, it is the practice to buy thread in relatively large rolls or tubes which thread is taken 25 from the rolls or tubes and wound on the bobbin as occasion may require. The thread is delivered to the factories in the form of large rolls or tubes which when not in use are set on shelves or on the tables of machines until such time as the threading of a 30 bobbin is necessary whereupon the rolls or tubes are manually manipulated into position to thread the bobbin and after the threading is completed the rolls or tubes are 35 once more placed on shelves or on a table of a machine. The handling of these rolls or tubes loosely, as is the universal practice, causes the thread to become soiled and in most large factories one or more of these 40 rolls or tubes of thread may be found on the floor at any time. Long before the roll or tube is completely used, the thread becomes loosened thereon and slips from the end of the roll or tube and becomes tangled 45 in such condition that it is unfit for use and it is not uncommon for whole rolls or tubes of such thread to be inadvertently gathered up with sweepings and thrown away. This 50 practice is very wasteful in thread and no means is provided in the large manufacturing 55 establishments for either conserving the thread by eliminating waste or maintaining the thread wound prior to its winding on the bobbin.

With the foregoing considerations in

mind, the object of the present invention is to provide a neat, compact and efficient receptacle or holder, one of which is adapted to be associated with each machine and in a position convenient to the bobbin, though 60 so conveniently positioned that it will not become an obstruction to the operator of the machine. A roll or tube of thread is adapted to be housed within the casing which is provided with an outlet reaching into proximity with the bobbin of the machine and the thread is threaded through this outlet and only a short end thereof normally protrudes therefrom. When it is desired to 65 thread a bobbin, this short end is carried to 70 the bobbin, secured thereto and the winding thereupon proceeded with. At the conclusion of the winding thread is cut off close to the outlet of the casing and left in 75 convenient position for winding the next bobbin.

At all times, however, the roll or tube of the thread is housed within the casing and maintained in clean condition and in such 80 form as to preclude tangling or wasting of the thread.

The casing is so formed as to enable a roll or tube of thread to be readily introduced thereto when the roll or tube previously 85 therein has been exhausted.

In the preferred practical form of the invention, the casing is of cylindrical form and is mounted on the under side of the table of a machine by means of a suitable bracket. Extending upwardly from the casing 90 is an outlet channel or passage which terminates in an outlet tube extending into proximity with the bobbin. Both the casing and outlet passage are diametrically divided and the parts are hinged together so that 95 one half of the casing and outlet passage may be swung back on a pivot to permit a roll of thread to be positioned within the casing after which the sections are closed with respect to one another and a spring 100 brought to bear against one end of the roll or tube for the purpose of adjusting the tension under which the thread is placed while being pulled from the roll and wound upon the bobbin.

The device is simple in construction, economical to manufacture and fulfills a long felt want in manufactures where large quantities of thread are used. The thread is kept clean and wasting is precluded.

Features of the invention, other than those specified, will be apparent from the hereinafter detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a perspective view of the device of the present invention showing the casing in opened condition, and,

Figure 2 is an end elevation of the device showing the casing in closed position and mounted on a table of a machine.

Referring to the drawings, 1 designates a cylindrical casing parted diametrically in a vertical plane to divide the section into two parts 2 and 3, which are hinged together as shown at 4. One end of the casing is closed by a circular disc 5, one half of which is rigidly secured to the section 2 and the remaining half of which is loose with respect to the section 3. The opposite end of the casing may be closed by a flat plate or disc adapted to bear against the end of the sections 2 and 3 but unattached to either.

The casing is adapted to be mounted on the table 6 of the machine by means of a bracket 7 of any suitable form. This bracket is secured to the section 2 of the casing and is adapted to be permanently fixed to the table of the machine by means of screws or bolts 8.

Extending coaxially of the casing and rigidly fixed in the end plate 5 thereof is a bolt or axle 9. This bolt is somewhat longer than the casing and is adapted to extend through the perforation in the opposite end plate of the casing and for an appreciable distance beyond this end plate. The bolt 9 provides a support for a roll or tube of thread 10, the thread being wound upon a suitable carrier or bushing 11 adapted to fit over the bolt 9 as shown in Figure 1. The desired tension may be applied to the roll by means of a helical spring 12 coiled about the end of the bolt 9 exteriorly of the end plate of the casing and this spring is placed under the desired tension by means of an adjustable collar 13 adapted to be locked on the bolt in any desired position by means of a set screw 14. In lieu of the collar 13 however the end of the bolt may be threaded and a nut screwed upon the bolt for the purpose of placing the spring 12 under the desired tension.

Extending upwardly from the top of the casing is an outlet duct 15 which at its base, where it joins the casing, is substantially equal in width to the length of the casing, but from this point the duct tapers upwardly to a substantially circular section 65 and is bent preferably on the arc of a circle

in the direction of the bobbin 16 of the associated machine. This bobbin is shown in dotted lines at 16. The outlet duct is divided centrally into two sections 17 and 18, the former of which is rigid with the section 2 of the casing while the latter of which is rigid with the section 3 of the casing. Moreover, the outlet duct terminates in an outlet or guide tube 19, the free end of which extends into proximity with the bobbin 16. This guide tube is mounted rigidly on the section 15 of the outlet duct and once the casing is closed and the sections of the outlet duct in assembled relation, the free end of the outlet duct section 18 will abut the rear end of the guide tube 19, so as to form a closed passage from the interior of the casing to the outlet end of the guide duct 19.

When it is desired to position a roll of thread in the casing, the collar 13 and spring 12 are removed and a roll thereupon passed over the bolt 9. During this operation, the section 3 of the casing and the section 18 of the outlet duct are swung back on the pivot 4 to permit this operation to be conveniently carried out. After the thread roll 10 is in position on the bolt 9, the free end of the thread, designated in the drawings by the reference character 10^a, is led upwardly through the open side of the section 17 and threaded through the guide tube 19, after which the casing is closed. That is to say, the section 3 is swung upwardly on the pivot 4 until the section 18 of the outlet duct comes into face abutting relation with the section 17 of the duct.

During this operation, the section 18 will be gripped by spring fingers 20 mounted on the section 17 and these spring fingers will tightly maintain the duct and casing in closed position. The under plate, not shown, is next applied to the open end of the casing and thereafter the spring 12 is placed over the end of the bolt and the collar 13 brought into position and locked in place by the set screw 14 to place the spring under the desired tension. The casing is made of such length that the under plate will bear against the end of the roll and so that the tension of the spring may cause the under plate to vary the friction between the roll and said plate and thus place the thread as it is drawn through the guide tube 19 under the desired tension.

The parts are preferably made of sheet metal so that the end tube is more or less resilient and properly permits of its operation.

At the conclusion of the operations described, a short length of thread is left hanging from the outer end of the guide tube 19, so that when a bobbin requires threading, this end may be lead to the bobbin, secured thereto and the threading op-

eration carried out. When this threading operation is concluded, the thread is cut adjacent the bobbin and a free end is left hanging from the end of the tube 19 ready for subsequent winding operation.

It will be apparent from the foregoing detailed description of the invention that it is of marked utility for the purpose stated and that it not only keeps the thread perfectly clean but also provides a housing and holder for the thread so that it is protected against unraveling or tangling with the result that there is no loss or waste.

The drawings show the invention in its preferred practical form, but the invention is to be understood as fully commensurate with the appended claims.

Having thus fully described the invention, what we claim as new and desire to set 20 cure by Letters Patent is—

1. A device of the character described embodying a casing divided longitudinally into two lateral sections hinged together, an axle associated with the casing and adapted to support the roll or tube of thread within the casing, a tubular outlet duct forming a passage for the thread and extending into proximity with a bobbin of the machine with which the device is 25 adapted to be associated, said duct being parted into two sections which are respectively supported on the two hinged sections of the casing, and means for maintaining the sections of the casing and outlet duct normally in closed relation.

2. A device of the character described embodying a casing divided longitudinally into two lateral sections hinged together, an axle associated with the casing and adapted to support the roll or tube of thread within the casing, a tubular outlet duct forming a passage for the thread and extending into proximity with a bobbin of the machine with which the device is adapted to be associated, said duct being parted into two sections which are respectively supported on the two hinged sections of the casing, means for maintaining the sections of the casing and outlet duct normally in closed relation, and a bracket mounted on the casing and adapted to be secured to said machine to permanently mount the device thereon.

3. A device of the character described embodying a casing divided longitudinally into two lateral sections hinged together, an axle associated with the casing and adapted to support the roll or tube of thread within the casing, a tubular outlet duct forming a 55 passage for the thread and extending into proximity with a bobbin of the machine with which the device is adapted to be associated, said duct being parted into two sections which are respectively supported on the two hinged sections of the casing, means

for maintaining the sections of the casing and outlet duct normally in closed relation, and means for applying friction to the thread to control the tension under which the thread is drawn from the casing.

4. A device of the character described embodying a casing divided longitudinally into two lateral sections hinged together, an axle associated with the casing and adapted to support the roll or tube of thread within the casing, a tubular outlet duct forming a passage for the thread and extending into proximity with a bobbin of the machine with which the device is adapted to be associated, said duct being parted into two sections which are respectively supported on the two hinged sections of the casing, means for maintaining the sections of the casing and outlet duct normally in closed relation, a spring, and tension adjusting 70 means cooperating with the spring for imposing pressure upon the roll for the purpose of regulating the tension under which the thread is withdrawn from the casing.

5. A device of the character described embodying a cylindrical casing having a shaft extending coaxially therethrough and rigidly mounted in one end of the casing, said casing being diametrically divided into two sections pivotally secured to one another, an outlet duct extending from the casing and divided longitudinally into two sections rigid with respect to the corresponding sections of the casing, means for normally maintaining sections of the duct 80 and casing in closed relation, a thread directing member carried by one section of the outlet duct and extending into proximity with the bobbin of a machine with which the device is adapted to be associated.

6. A device of the character described embodying a cylindrical casing having a shaft extending coaxially therethrough and rigidly mounted in one end of the casing, said casing being diametrically divided into two 90 sections pivotally secured to one another, an outlet duct extending from the casing and divided longitudinally into two sections rigid with respect to the corresponding sections of the casing, means for normally maintaining sections of the duct and casing 95 in closed relation, a thread directing member carried by one section of the outlet duct and extending into proximity with the bobbin of a machine with which the device is adapted to be associated, and means for varying the tension of the thread supported on said axle and extending through the outlet duct and directing member.

In testimony whereof we have signed the 100 foregoing specification.

MAX GILBERT.
THOMAS GUIDA.
SOLOMON KATZ.
